GAME BOARD

Israel R. Paris, Washington, D. C.

Application April 4, 1938, Serial No. 199,954

4 Claims. (Cl. 35—8)

The present invention relates generally to means and devices for self-instruction in the game of bridge, and more particularly to the type of device which comprises a plate having suitable slots which permit the display therethrough of card insignia arranged in four pre-selected hands which constitute a bridge game.

One object of the invention is to provide a book whether in loose leaf form or otherwise in which each leaf or page has a bridge game or deal printed thereon and discussed, the book also having associated therewith a plate suitably slotted to display the card insignia therethrough, the plate also carrying movable devices to indicate whether any given card has been played or remains to be played and which generally aid in indicating the progress of the game.

Another object is to provide an improved construction of the plate.

Another object is to construct a plate of this type so that it is double faced and may be employed with either face up.

In the drawings—

Fig. 1 is a plan view of the device secured in a book;

Fig. 2 is a section on the line 2—2 of Fig. 1; Fig. 3 is a section on the line 3—3 of Fig. 1;

Fig. 4 is a section on the line 4—4 of Fig. 1;

Fig. 5 is a detail perspective of one of the slider members;

Fig. 6 is a detail perspective of the trick indicating slider;

Fig. 7 is a fragmentary plan view of a further modification;

Fig. 8 is a section on the line 8—8 of Fig. 7;

Fig. 9 is a section on the line 9—9 of Fig. 7;

Fig. 10 is a detail perspective of one of the

sliders used in the modification of Fig. 7.

The plate 10 shown in the drawings will be seen to be substantially flat on both faces with practically no projections therefrom with the result that when the same is employed as part of a book or in association with a book it may be employed in the book between the pages thereof without causing any injury to the book. The book may also be closed, with the plate between its pages, without any injury to the book. If desired, the plate may constitute or be an external part of one of the covers of the book and by virtue of the fact that the plate contains no projecting parts from its operating face or faces, the book may be disposed on

a book shelf in the customary manner without any injury to adjacent books.

For these purposes, the sliders 12 which indicate the course of play of the game, as well as the sliders 14, which indicate the score, and other sliders, which may be desirable for the purpose of displaying other printed information on the page or leaf, such as the progress of the bidding, are all disposed in such a manner that while they are manipulated with great facility, they do not have any parts that project from the face of the plate to any such extent as to injure adjacent books on the book shelf when the plate 10 constitutes part of a cover, or to injure the pages of the book when the same is closed with the plate disposed between its pages. For this purpose, the sliders 12 and 14 are disposed within the plate, each of the sliders consisting of a substantially flat thin metal plate having means in the form of a slight protuberance, such as the bent edge 16 or the rib 18 which serves as a ready means for manipulating the slide from one position to the other. If desired, in lieu of the edge 16 or rib 18 the sliders 12 may simply be provided with a small aperture 20 so that a pencil or any stylus may be employed for moving the slide from one position to the other.

The present plate 10 consists of two rectangular sheets 22 and 24 with an interposed separator 26 which in the form shown herein may also be in the form of a suitably slotted sheet. These are preferably made of metal, it being obvious, however, that the same may be made of any other suitable material.

The plates 22 and 24 are each provided with four series of elongated slots 28 disposed along the sides of a rectangle for the purpose of displaying the card insignia therethrough of the hands. Each of these slots has an opening or window 30, as shown, for the purpose of displaying the numbers appearing on the printed page or sheet next to the card insignia, which numbers indicate the correct order of play of each hand. Obviously, the openings 30 may constitute one elongated slot disposed parallel to the slots 28, or, if desired, the slots 28 may be lengthened so that they will display the numbers as well as the card insignia. In the preferred form, however, the sliders 12 are so arranged that they are each slidable from one extreme position to the other, displaying the card in one position while concealing the number associated therewith, and displaying the number in the other position while concealing the card.

The plates 22 and 24 each also have a pair of slots 32 which serve to expose sliders 14, one in each slot, which are movable to indicate the tricks taken by the two sides of the game.

- 5 The spacer plate 26 preferably has a series of rectangular apertures 33 in registry with each slot 28. At one end the apertures 33 extend into the space between the plates 22 and 24 and beyond the openings 30 in such plates. It will now be understood that the sliders 12 are each substantially longer than the slots 28 so that when the sliders are in the position where they conceal the card insignia, they are, nevertheless, well supported and kept in position between the adjacent portions of the plates 22 and 24. At the same time, the partitions 34 between the apertures 33 serve as guides for these slides. When the slides are in the other extreme position, the cards are exposed and the sliders cover or block sight through the openings 30 so that the numbers are concealed.
- 10
- 15
- 20
- 25

As shown the sliders 12 have at one end an upturned edge 16 and a rib 18. These serve to permit their ready operation from either side of the board or plate 10.

The spacer sheet 26 also has a pair of slots 38 which correspond to the slots 32 in plates 22 and 24 but larger than the slots 32 so as to receive the slider 14 which moves longitudinally of the slot 32.

- 30 The slide 14 has stamped or embossed or die punched two arrow shaped protuberances 40, one in relief on one face and the other in relief on the other face, with the result that it may be engaged from either face for movement. Each 35 of the slots 32 on each face of the board 10 is provided with a series of numbers, one to thirteen, so that the position of the slide 14 indicates the number of tricks taken by each side.

If it is desired to provide some additional friction for the sliders 12 a punch mark in the concealed end will form a slight projection which will serve this purpose; or, if desired, a short cut in the concealed end of the slide will cause it to spread sufficiently so that the concealed corners 45 will frictionally engage the partitions 34.

The sheets 22, 24, and 26 are associated together as by riveting, soldering, brazing, or spot welding so that they together constitute substantially rigid and unitary structure with the slides 12 retained within this unitary rigid structure, the slides being readily manipulable, sufficient friction being provided for retaining the same in either position.

As shown and described, the board 10 is so constructed that it may be employed with either face up or down; this is for the purpose of permitting of the use of the board inside a book and particularly inside a loose leaf book where each page has the desired printed data. For use in such a loose leaf book, the plate or board 10 may have two or more openings 42 along one edge thereof which will engage the customary loose leaf rings 44, or the like. Thus the board may be inserted inside the book and used with either of the adjacent pages containing bridge deals. When the player has completed his study of these deals, he readily transfers the board so that he may play or study the next two deals. The engagement of the board with the rings 44 serves to register the board with relation to the printed data on the adjacent pages.

It will be understood, however, that for other purposes it is unnecessary to make the board double faced. In that case the sliders 12 are provided with lugs or some such other protuberance only on one face. If the board is not intended to

be used in association with a book, then the protuberances or lugs on the sliders 12 may be enlarged and may project substantially beyond the face of the board. When the board is only single faced, the slider 14 has only one protuberance 40, 5 and the bottom plate does not have the slot 32.

Another form of board is shown in Fig. 7. In this form of board the slots or sight openings are such that they are big enough to display both the card insignia and the numbers associated therewith which indicate the order of play. The sliders in the present construction are always disposed wholly within such sight openings and are slideable from the position covering the number to the position covering the card and vice versa. 15

In this form the intermediate spacer plate 60 has the openings 62 as shown with the narrow partitions 64 disposed between adjacent windows in each hand. The upper and lower plates 66 have corresponding openings 68, each of the 20 same length as the openings 62, but are each somewhat narrower because the partitions 70 are somewhat wider than the partition 64 and extend somewhat laterally from each edge. Thus, the partition 70 of the upper and lower boards together form guides for the sliders 72, which are disposed in the plane of the intermediate plate 60, and have their edge portions disposed between the juxtaposed partition 70. The ends of the slider 72 each have an angular portion 74, one 30 turned in one direction and the other in the opposite direction. One flange 74 rides between the edges of the partitions 70 in the upper plate and the other in the lower plate. These flanges may be employed for the manipulation of the sliders 35 or the sliders may be provided with other means for that purpose, such as a stylus receiving aperture or any other desired means. The slides may each have fish tails 76 formed by apertures 78 and slots 80. These fish tails 76 when strained laterally will press yieldingly against the edge of the adjacent partition 64 and supply the necessary friction for retaining the slides in one or the other position. Obviously, other means may be employed for this purpose. 45

These three plates together with the slides are assembled and secured together in any manner desired as described herein so that a rigid board is obtained with the slides indicating the progress of the play readily manipulable. 50

It will now be understood that the present invention provides a rigid board which, although made of three metal sheets, has the appearance and effect of a unitary construction. It will further be understood that the present board may be made of sheets of any other desirable or suitable materials which can be associated together so as to provide a rigid board. 55

One of the important features of the present construction is that it provides a game board of 60 the type described which has a plurality of sight openings and sliders having portions which are captured within recesses in the walls facing the openings. As shown, it is contemplated that these sliders should be captured within the board 65 during its assembly. While the invention claimed herein is illustrated and embodied in a bridge board it will be understood that the same may be employed in many other game boards which are employed in association with sheets 70 bearing printed data for display through sight apertures in the board.

Having thus described my invention, I claim:

1. A game board having a plurality of through sight openings for cooperation with a sheet bear- 75

ing printed data in registry with said openings, said board comprising a pair of outer plates each having a plurality of sight openings, an intermediate plate also having a plurality of sight openings greater in at least one dimension than the corresponding dimension in the openings of the outer plates, said plates being superposed with the intermediate plate disposed between the outer plates with the openings in registry, and sliders slidable in said through sight openings and held between the outer plates.

5 2. A game board having a plurality of through sight openings for cooperation with a sheet bearing printed data in registry with said openings, said board comprising a pair of outer plates each having a plurality of elongated sight openings, an intermediate plate also having a plurality of corresponding openings approximately twice the length of the other openings, said plates being coextensive in area and permanently associated together, with the intermediate plate disposed between the outer plates with the openings in registry, and sliders longer than the openings in the outer plates, said sliders being disposed between the outer plates and slidable in said openings to open or close the said through sight openings.

10 3. A game board having a plurality of through sight openings for cooperation with a sheet bearing printed data in registry with said openings, said board comprising a pair of outer plates each

15 having a plurality of elongated sight openings, an intermediate plate also having a plurality of corresponding openings wider than the other openings, said plates being coextensive in area and permanently associated together with the intermediate plate disposed between the outer plates with the openings in registry, and plate-like sliders of approximately the width of the openings in the intermediate plate, said sliders being disposed in the openings in the plane of the intermediate plate and slidable therein, each of said sliders having a lug to facilitate sliding.

20 4. A game board having a plurality of through sight openings for cooperation with a sheet bearing printed data in registry with said openings, said board comprising a pair of outer plates each having a plurality of elongated sight openings, an intermediate plate also having a plurality of corresponding openings wider than the other openings, said plates being coextensive in area and permanently associated together with the intermediate plate disposed between the outer plates with the openings in registry, and plate-like sliders of approximately the width of the openings in the intermediate plate, and approximately half the length of the openings in the outer plates, said sliders being disposed in the openings in the plane of the intermediate plate and slidable therein, each of said sliders having a lug to facilitate sliding.
